CONTAINER CLOSURE

Guy O. Conner, Wheeling, W. Va., assignor to
Wheeling Steel Corporation, Wheeling, W. Va.,
a corporation of Delaware

Application August 6, 1936, Serial No. 94,630

5 Claims. (Cl. 220—59)

This invention relates to a closure for containers such as drums, pails or the like and, in particular, to a cover which is inexpensive to manufacture and capable of being firmly secured to the container.

Container closures of various types are now in use, but each is characterized by certain objectionable features. Certain closures have been provided with a so-called "ring type" seal where-
5 in a flanged cover is secured to a container by a frangible clamping ring or channel. While this is a very effective form of seal, it is relatively expensive. Lug-type closures have also been used but have been found lacking in effective sealing qualities. A further objection is that the operation of bending the holding lugs often mars the finish on the container which is undesirable.

I have invented a closure which overcomes the
20 aforementioned objections to such articles as previously manufactured. In accordance with my invention, I provide a closure comprising a central or body portion surrounded by a pressed groove or channel adapted to receive the false wire around a container opening when the closure is placed thereover. The extreme edge of the closure, i. e. the outer wall or side of the groove or channel, is provided with cut-outs which facilitate crimping the edge around the
25 false wire. Preferably, the cut-outs are spaced inwardly of the edge of the closure, and the material between the cut-outs and the closure edge is displaced slightly from its original plane.

A present preferred embodiment of the invention is illustrated in the accompanying drawing. In the drawing,

Fig. 1 is a partial plan view of a closure in accordance with the invention;

Fig. 2 is a partial elevation;

40 Fig. 3 is a sectional view along the line III—III of Fig. 2;

Fig. 4 is a sectional view along the line IV—IV of Fig. 2;

Fig. 5 is a partial plan view of the closure
45 applied to a container;

Fig. 6 is a partial elevation thereof;

Fig. 7 is a sectional view along the line
VII—VII of Fig. 6; and

Fig. 8 is a sectional view along the line
50 VIII—VIII of Fig. 6.

Referring now in detail to the drawing, a closure in accordance with my invention comprises a central or body portion 10. A downwardly displaced bead 11 surrounds the central portion 10, and contributes rigidity thereto. A channel or

groove 12 is formed beyond the bead 11. The closure is preferably drawn from flat sheet metal stock in suitable drawing dies. The groove or channel 12 is adapted to receive the false wire of a container when the closure is placed thereon. 5 Figs. 7 and 8 show a container 13 having a false wire 14 surrounding an opening therein or an open end thereof.

The outer side or wall 15 of the channel 12 is provided with cut-outs 16. These cut-outs are 10 preferably spaced inwardly of the extreme edge of the flange formed by the wall 15, and the material between the edge of the flange and the cut-outs is slightly displaced out of its normal plane forming loops 17. The cut-outs are pref- 15 erably triangular in shape as shown, having one edge parallel to the edge of the flange or wall 15, for a purpose which will appear later, but may be simply slits parallel to the flange edge.

The closure may be applied to a container as 20 already indicated and, if desired, a sealing gasket may be disposed in the groove 12 for engagement with the false wire 14. When the cover has been seated on the container and pressed down tightly, the edge of the flange or wall 15 is bent 25 around the false wire, as shown in Figs. 7 and 8. This operation crimps the edge of the flange 15, partly closes the triangular cut-outs 16, and increases the extent to which the loops 17 are displaced from the normal plane of the flange 15. 30 It will be observed that the extreme edge of the flange 15 clears the side wall of the container 13, so that the finish on the latter will not be marred by the sealing operation. The flange 15 may be bent around the false wire by any con- 35 venient means already known.

Although the closure thus applied effectively seals the container, it can be easily removed. The flange 15 may easily be bent outwardly by the insertion of any sharp instrument in, say 40 every fifth loop or eye 17, and pulling up on the outer end of the instrument. With the flange thus straightened, the closure can readily be freed from the container, as by tapping the flange 15 with a hammer.

The closure described and illustrated herein can be made at a cost lower than that of lug-type covers or plain covers plus a ring-type seal for cooperating therewith. In addition, it is more effective in sealing a container than a lug-type 50 cover, and the application thereof to the container does not mar the finish on the latter.

Although I have illustrated and described but one preferred form of the invention, it will be apparent that changes therein may be made with- 55

out departing from the spirit thereof or the scope of the appended claims.

I claim:

- 5 1. A container closure having a continuous down-turned peripheral flange, holes spaced along said flange and inwardly of the edge thereof, portions of said edge being bent outwardly of the general plane of said flange adjacent said holes only.
- 10 2. A container closure having a continuous down-turned flange adapted to be curled around the false wire of a container, holes adjacent the flange edge forming lugs therebetween capable of bending inwardly without interference with each other, the edge of the flange being continuous across said holes, but bent out of the general plane of the flange adjacent the holes.

3. A container closure comprising a body portion and down-turned flange thereon, with perforations spaced slightly from the flange edge, the edge being deformed outwardly adjacent the perforations only.

4. The closure defined by claim 3 characterized by said perforations having an edge parallel to the edge of said flange.

5. A sheet metal closure comprising a central portion, a peripheral groove or channel, and perforations adjacent the outer edge of the groove, but spaced slightly therefrom, the edge of the closure being displaced from its initial position adjacent said perforations to facilitate crimping said edge around the false wire of a container. 15
